Inventor,
Alfred Wilkin

United States Patent Office.

ALFRED WILKIN, OF LUCAS COUNTY, OHIO.

Letters Patent No. 91,190, dated June 8, 1869.

FIRE-PLACE.

The Schedule referred to in these Letters Patent and making part of the same.

To all whom it may concern:

Be it known that I, ALFRED WILKIN, of Lucas county, in the State of Ohio, have invented a new and improved "Smoke-Burning Radiator," of which the following is a clear, full, and exact description, reference being had to the accompanying drawings, making a part of this specification, in which—

Figure 1 is a front view of the radiator.

Figure 2 is a vertical sectional view on the line $x-x$.

The object of my invention is to provide a cheap burner, which will consume the smoke, prevent waste, and throw out increased heat from a perfect combustion of the gases.

In addition to this, my burner is so arranged, as to increase the draught of the flues, as well as to furnish more heat from the same amount of fuel consumed, than any other grate now in use.

To enable others skilled in the art to understand and use my invention, I will proceed to describe the manner in which I have carried it out.

In the said drawings—

A represents a cast-iron face, or front to the fire-place.

B is an ordinary grate, for holding the fuel.

Plate D, which forms the back of the fire-place, is of cast-iron, of suitable thickness, say, about one-half inch thick on the lower edge, and about one-fourth of an inch thick at the top.

This plate is cast with projections $q q$, by which it is secured in the brick-work, and with a series of holes, or openings, H H, ranging nearly on a level with the top of the grate B, and another row of these openings, C C, above the curve G, and near the flange of the plate D, on which rest the bricks a a, which complete the throat of the flue.

The plate D is set about three inches in front of the brick back to the fire-place, of ordinary construction,

and is provided with hooks, or lugs M M, on which is rested the rear of the grate B.

By this construction, a free passage of oxygen, or air, is admitted over the ash-box, and under the plate D, at the point K; or the air may be admitted from the cellar of the room, or from the outside of the building, as may best suit the convenience or judgment of the builder.

It is evident, the air behind the plate D, and between it and the brick back of the fire-place, will become heated, and will be forced, by expansion, through the perforations H H, where, coming in contact with the heated carbon, it will immediately ignite.

The curve G, at the upper part of the plate D, is for the purpose of thoroughly incorporating the oxygen and carbon, and, by the introduction, again, of more heated air through the perforations C C, securing a perfect combustion of the escaping gases.

This arrangement increases the draught of the flues, as well as furnishes more heat from the same amount of fuel, than any other grate known.

By the admission of air, in the manner described, in connection with the form of the plate D, is furnished a powerful radiator, far surpassing any now in use, and one which can be put in old flues, or built in new, with but little inconvenience, and at a trifling cost.

What I claim as my invention, and desire to secure by Letters Patent, is—

The plate D, with its curve G and perforations H H and C C, in combination with the grate B, and when constructed with reference to the back of an ordinary fire-place, substantially as and for the purpose described.

ALFRED WILKIN.
